ATTORNEY

UNITED STATES PATENT OFFICE

168,527

HELMET OR THE LIKE

Narvelle Arant, Larkspur, Calif., assignor to Arant Plastics, Inc., San Francisco, Calif., a corporation of California

Application November 29, 1951, Serial No. 17,567

Term of patent 14 years

(Cl. D3—13)

To all whom it may concern:

Be it known that I, Narvelle Arant, a citizen of the United States of America, residing at Larkspur, Marin County, State of California, have invented a new, original, and ornamental Design for a Helmet or the like, of which the following is a specification, reference being had to the accompanying drawing, forming a part thereof.

In the drawing:

I claim:

The ornamental design for a helmet or the like, as shown.

NARVELLE ARANT.
